JOHN H. COBURN, OF LOWELL, MASSACHUSETTS.

Letters Patent No. 97,882, dated December 14, 1869.

IMPROVEMENT IN SHUTTLE FOR LOOMS.

The Schedule referred to in these Letters Patent and making part of the same.

To all whom it may concern:

Be it known that I, JOHN H. COBURN, of Lowell, in the county of Middlesex, and State of Massachusetts, have invented certain new and useful Improvements in Shuttles for Looms, of which the following is a full, clear, and exact description, reference being had to the accompanying drawings, making part of this specification, in which—

Figures 1 and 2 are central longitudinal sections, the former with a filling-bobbin, (as employed,) on the spindle, and the latter without it.

Figure 3 is a similar section, with the spindle in position to receive the bobbin.

Figures 4 and 5 are detached spindles, with the springs and holding-projections clearly shown.

This invention and improvement in shuttles relates to the spindle which holds and carries the filling-bobbin, and has for its object to facilitate the removal of empty bobbins, and the replacing of full ones, without unnecessary wear and injury to the bobbin; to hold the bobbin firmly on the spindle, and always in the same line of action, or parallel with the longitudinal central line of the shuttle, and to prevent the possibility of the bobbin being accidentally released or disengaged from the spindle, while the shuttle is in use, or while ready for use.

In constructing and applying my said improvement, the top side of the spindle A is flattened, from the shoulder a, to near the end b thereof, and the spring d is fitted and fastened to the flattened side of the spindle.

This spring d is so formed that the end e is raised from the flattened surface by its own rigidity, and requires considerable pressure to force it down and hold it while the bobbin is placed upon the spindle.

The pressing down of the free end of the spring is performed by the end f of the top plate or top spring, as shown in fig. 3, where the spindle is raised or turned upward to receive the bobbin.

Here it will be seen, that when the spindle is turned upward or outward, the free end of the spring d comes in contact with the under side of the end of the top plate or top spring, which acts upon the pivoted head of the spindle, and presses the spring d downward on to the flattened surface of the spindle, and allows the bobbin to slide freely on to the same.

Pushing on the free end of the spindle moves or turns it downward (with the bobbin upon it) into the shuttle, which operation releases the end of the spring d from contact with the end of the top plate, and al-

lows the end of the spring d to rise and bind the bobbin on to the spindle.

This binding action of the spring d is not sufficient to hold the bobbin on to the spindle, under all circumstances, and therefore I form a holding-projection, e, either on the top side of the spring d, as shown in fig. 4, or in the free end of the spindle, as shown in fig. 5. In the former case, the projection e on the spring, rises into an annular groove, g, formed within the bobbin, and holds it on to the spindle, and in the latter case, the projection e on the free end of the spindle, engages with or hooks on to the end of the bobbin, being forced into that holding-position by the action of the spring d, which raises the rear end of the bobbin, and forces the forward end down on the top of the free end of the spindle, and back of the projection e, which fully engages with the end of the bobbin.

In either case, the spring d holds the bobbin steady on the spindle, and in the line of action of the shuttle, and prevents it rotating on the spindle, when the filling-runs off, while the projection e retains the bobbin on the spindle, against any action of the shuttle, and prevents the possibility of the bobbin being released, or becoming disengaged from the spindle, unless at the will and by the action of the operator, who may raise or turn the spindle and the bobbin upward, which brings the free end of the spring d in contact with the under side of the end f of the top plate, which presses the spring d on to the flattened surface of the spindle, as shown in fig. 3, when the bobbin may be removed, and another bobbin replaced on the spindle, with ease and convenience.

My improvements can be readily applied to almost any kind of shuttle, without the least change or alteration in the construction of the shuttle, or in the construction or application of any of the parts thereof.

Any other device may be arranged to compress the end of the spring d, but the end of the top plate is a convenient device for that purpose, and avoids the necessity of adding other parts to the shuttle.

What I claim as my invention, and desire to secure by Letters Patent of the United States, is—

The spindle A, provided with the spring d, constructed substantially as described, and with the holding-projection e, whether on the spring d, or on the end of the spindle A, for the purposes set forth.
